DISPLAY CAP HANGER

Filed Dec. 12, 1922

Whitness,
Erwin B. Eiring

UNITED STATES PATENT OFFICE.

HILDA A. NIEBLER, OF RACINE, WISCONSIN.

DISPLAY CAP HANGER.

Application filed December 12, 1922. Serial No. 606,414.

To all whom it may concern:

Be it known that I, HILDA A. NIEBLER, a citizen of the United States, and resident of Racine, in the county of Racine and State of Wisconsin, have invented certain new and useful Improvements in Display Cap Hangers; and I do hereby declare that the following is a full, clear, and exact description thereof.

10 This invention relates to display cap hangers.

In displaying caps difficulty has been encountered in exposing a sufficient number of caps to view without taking up an excessive amount of room. Further than this, caps are not easily positioned upon stands, unless separate stands are employed for each cap, and when the caps are placed upon shelves or tables, only the uppermost cap of 20 each pile is displayed. In addition to this such a mode of display presents an unsightly appearance and one not likely to appeal to a prospective purchaser.

This invention is designed to overcome the above noted difficulties and to provide a display cap hanger which will hold the cap in an easy and neat manner, which may be readily suspended from racks or rods, which will permit a large number of caps to be 30 displayed without requiring an excessive amount of room, which can be made at an extremely small cost, and which may be readily positioned within and removed from the cap.

35 An embodiment of the invention is shown in the drawings, in which,

Figure 1 is a rear view of the hanger showing the cap in dotted lines.

Figure 2 is a sectional view on the line 40 2—2 of Figure 1.

Referring more particularly to the drawings, it will be seen that the display cap hanger is composed of a wire frame. This frame is formed by bending a wire to provide a substantially horizontal slightly downward slanting portion 1, curving such wire as indicated at 2, bending the wire upwardly to form a re-entrant angle or dent 3, thereafter forming a similarly curved portion 4 upon the opposite side of the frame and a corresponding substantially horizontal or slightly slanting portion 5 corresponding to the portion 1. The end of the wire is looped around an intermediate portion of 55 the upper side of the frame, as indicated at

6, to secure such end in position. The other end of the wire extends downwardly from this point, as indicated at 7, and is hooked into the dent or re-entrant angular portion 3 and slightly kinked, as indicated at 8, to lock such side portion. Thereafter this end extends at right angles to the plane of the frame, as indicated at 9, and thence upwardly, as indicated at 10, terminating in attaching eyelet 11. This eyelet, of course, 65 may be either open or closed, and in the form shown is opened, somewhat in the nature of a hook.

It will be seen that the last described end of the wire supports both the upper and the 70 lower side of the looped frame, and is spaced from such looped frame as may be seen from Figure 2. This construction provides a place for the reception of the visor 12 and the adjacent portion of the cap 13.

75 It will be seen, therefore, that a display cap hanger has been provided in which a looped wire frame conforms to the curved interior contour of the front inner portion of the cap, and in which a support for such frame is provided and spaced from the frame a distance sufficient to accommodate the appropriate portion of the cap.

It is intended that this frame shall be used 80 to support caps in a neat and effective manner, so that they may be readily supported from rods or bars, such as continuous frame having a series of parallel rods, for instance. Upon these rods, the caps may be suspended completely around the frame and in successive rows, if desired. If desired, the eyelets 85 of course may be hooked upon suitable pegs, thereby properly and securely retaining the cap in display position. Other uses of the device will readily suggest themselves to 90 anyone skilled in the art.

95 Although a specific form of the invention has been described in considerable detail, it is clear that the invention may be embodied in several different forms and such invention, therefore, is to be limited only as set forth in the appended claims.

I claim:

1. A display cap hanger comprising a closed looped wire frame having one end of 100 the wire secured at an intermediate point on the upper side of the frame and the other end of the wire extending from such point downwardly and hooked under the lower side of said frame and thence extending at right 105 110

angles to the plane of the frame and thereafter extending upwardly and terminating in an attaching eye.

2. A display cap hanger comprising a closed looped wire frame having one end of the wire secured at an intermediate point on the upper side of the frame and the other end of the wire extending from such point downwardly and hooked under the lower side of said frame and thence extending at

right angles to the plane of the frame and thereafter extending upwardly and terminating in an attaching eye, said lower side of the frame being bent to provide a re-entrant angle or dent at the point where said last mentioned end is hooked under such side. 15

In testimony that I claim the foregoing I have hereunto set my hand at Racine, in the county of Racine and State of Wisconsin.

HILDA A. NIEBLER.
